LAUNDRY MACHINE

John F. Horvath, Milwaukee, Wis., assignor to
Appliance Corporation of America, Milwaukee,
Wis., a corporation of Wisconsin

Application November 16, 1946, Serial No. 710,267

8 Claims. (Cl. 68—12)

1

The present invention relates to a laundry machine and more particularly to novel means and methods of supplying washing and rinsing fluids to a laundry machine container and of expressing such fluids from the container and the material being washed therein.

The invention is particularly adapted for use with a laundry machine of the type disclosed in my copending application Serial No. 725,299, to which reference is made for details not claimed in the present application, but it is to be understood that the present invention may be used with laundry machines of other types and kinds.

One object of this invention is to provide a novel nozzle in the central lower portion of the laundry container and which is adapted to supply wash and rinse water to the container and to drain part of such water therefrom. Another object is to provide a novel container or tub having a perforated top portion, and a pressure diaphragm therefor that will force water from the container by causing it to overflow, and then will squeeze and express the water from the material in the container and cause it to flow through the perforations in the top portion and through the nozzle.

Another object is to provide a novel fluid conduit system for a laundry machine having the above features and to provide automatic operation for such a machine.

Other objects are to provide a novel valve for controlling the nozzle, and novel vacuum breakers in the conduit system to prevent back flow of fluid therein.

Further objects will become apparent from the following detailed description taken in connection with the accompanying drawings illustrating a preferred form of the invention wherein:

Fig. 1 is a vertical central section through a laundry machine embodying the invention with the lower part thereof in elevation.

Fig. 2 is a fragmentary horizontal sectional view taken on the line 2—2 of Fig. 1.

Fig. 3 is a vertical sectional view taken on the line 3—3 of Fig. 1.

Fig. 3a is an enlarged fragmentary section of the connecting joint between the upper section of the tub and the diaphragm and the door supporting collar.

Fig. 4 is a reduced view similar to Fig. 3 of the washing container showing the parts during washing operation.

Fig. 5 is a view similar to Fig. 4 but showing the parts during extracting operation.

Fig. 6 is a schematic representation of the conduit system and the controls therefor.

2

Fig. 7 is an enlarged vertical sectional view of a vacuum breaker in position to relieve any vacuum behind the diaphragm or in the conduit system.

Fig. 8 is a view similar to Fig. 7 with the vacuum breaker in position to introduce wash or rinse water into the tub.

While my invention further resides in the combination, construction and arrangement of parts illustrated in the accompanying drawings, I have shown therein, for illustrative purposes only, a preferred embodiment, and wish it understood that the same is susceptible of modification and change without departing from the spirit and scope of the appended claims.

Referring to the drawings, 10 represents the casing or housing of a laundry machine having an upper compartment 11 housing the washing and rinsing container or tub 12, and a lower compartment 13 housing most of the operating mechanism. The housing is preferably mounted on a base 14, and its top 15 is provided with a central opening having a depending lip 16, and is adapted to be closed by a lid 17 attached by a hinge 18 to the under side of the top 15.

The container 12 is substantially spherical in shape and is preferably formed of a lower hemispherical section 19 and an upper hemispherical section 20, said sections having laterally extending flanged edges which are welded together to form the container 12. The lower container section 19 is provided with a bottom central opening and with two diametrically opposite ribs 21, 21 extending upwardly from such opening to the upper edge of the lower section. The vertical center lines of these ribs are in the same vertical plane and these ribs are each preferably formed integrally with the tub lower section, as shown in Fig. 2. The upper container section 20 is provided with a top central opening and with two diametrically opposite ribs 22, 22 extending upwardly from the lower edge of the section to a point adjacent to but spaced slightly from said opening. The vertical center lines of ribs 22, 22 are in the same plane and form continuations of the ribs 21, 21 when the sections are joined. The opening in the top is formed in a collar 23 attached as by bolts to an annular ring 24 between which collar and ring the upper edge of the upper section of the tub is clamped by said bolts.

The collar 23 is provided with an upturned lip 25 around the perimeter of the opening, and perforated door 26 is pivotally attached by a spring-pressed bolt 27 to the under side of collar 23. Door 26 is movable by handle 28 hinged to the

top of the door and provides a closure for the opening in the collar.

The container or tub is fixedly secured at its central bottom to a support member 29 on the top of a shaft 30, said support member being provided with a circular depression or well 31 in its top from which extends a threaded opening 32 which leads to an opening 33 in its side. A fitting 34 is threaded into the opening 33 and to it is connected a flexible hose 35 for a purpose to be hereinafter more fully explained. A nozzle 36 is threaded into the opening 32, this nozzle, as shown in Fig. 3, having a central bore 37 from which drain passages 38 extend to the exterior of the nozzle. The nozzle has a hollow conical perforated head 39 threadedly attached to its top, and the reduced lower end 40 threaded into a reduced diameter of opening 32 in the member 29 forms a shoulder portion 41.

A compression diaphragm 42 is adapted to be received in and cover the interior surface of the container or tub, as shown in Figs. 2 and 3. This diaphragm fits snugly over the ribs in the container and may be of rubber or other flexible material. Its upper edge is secured to the upper part of the container section 20, and is bent over to extend between the collar 23 and the exterior of the upper container section 20, and is clamped therebetween, and is also clamped between ring 24 and the interior of the tub, by the bolts passing therethrough. Its lower end is provided with a circular opening having a flange 43 extending therefrom which is bent over the adjacent edge of the container and clamped between the shoulder 41 of the nozzle and the bottom face of the depression 31, by screwing the nozzle downwardly thereagainst.

A pipe P is provided to conduct hot water and a pipe 44 with branch 45 is provided to conduct cold water to a mixing valve 46 in the lower compartment 13. This valve is controlled by a handle 47 preferably located on the top of the casing. From this valve a pipe 48 leads to a pipe 49 one end of which communicates with a valved chamber member 50 which also carries a selector valve member 51. From chamber 50 extends a pipe 52 having a vacuum breaker 53. From this vacuum breaker a pipe 54 connects with the hose 35 leading to the nozzle 36 previously referred to.

The cold water pipe 44 leads to a pipe 55 the opposite ends of which are connected to the rinse water supply valve 56 and the pressure fluid supply valve 57. The pipe 49 connects the rinse valve 56 with the chamber 50 of the selector valve 51, and pipe 58 leads from the pressure fluid valve 57 to a vacuum breaker 59 from which leads a pipe 60 leading to pipes 61 and 62 both of which are connected to pipe 63. Secured in pipe 62 is a check valve 65. One end of pipe 63 is connected to a hose 66 which in turn is attached to a fitting 67 communicating with interior of the lower tub section 19 (see Fig. 3). The other end of pipe 63 is connected to a part of the pressure fluid drain valve 68. From the other side of this drain valve a pipe 69 leads to a drain pump 70.

Connected by a suitable fitting to pipe 54 is a pipe 71 connected to the chamber 72 of the selector valve member 51. Extending from the other side of chamber 72 is a pipe 73 connected to pipe 74 which at its upper end is connected to the bottom of the compartment 11 within which the container is mounted. The lower end of pipe 74 is connected to pipe 69 which as stated above leads to the drain pump 70.

Mounted in the compartment 13 of the ma-

chine housing is an electric motor 75 connected with an electrical circuit 76—77, lead 77 of which extends to the terminal 78, and lead 76 of which extends through the switch 79 to the line 80 which leads to the terminal 81. Terminals 78 and 81 are preferably connected in a suitable plug adapted to be inserted in a wall socket or the like to receive electric current from any suitable source of supply. Switch 79 when closed contacts terminals 82 and 83 and when open breaks this connection to the motor.

Belt 84 is driven by motor 75 to rotate the pulley 85 which has a shaft 86 extending into the speed reducing gear casing 87 which is provided with speed reducing gearing of any suitable type, for example such as that shown and described in my said copending application, Serial No. 725,299, which is not being specifically claimed in this application and hence need not be described in detail. Sufficient to say that rotation of shaft 86 causes rotation of upstanding shaft 30 at a suitable speed for the desired rate of oscillation of the container or tub, and the speed reducing gearing referred to rotates the upstanding control shaft 88 at a much slower speed.

This speed ratio between the shafts 30 and 88 is selected so that the speed of shaft 88 is sufficiently slow to obtain the desired operating time for the various operations occurring during one complete cycle (one rotation of shaft 88) of introducing cleansing liquid into the container, cleansing the material to be cleansed in the container, draining the cleansing liquid from the container and squeezing the material being cleansed to extract liquid therefrom, introducing rinsing liquid into the container, agitating the material in the container with the rinse liquid, draining the rinse liquid from the tub, and squeezing the rinse liquid from said material.

These control cams are so fixed and arranged on the control shaft 88 that during a single complete revolution of this control shaft, the machine goes through a complete operating cycle referred to above, generally consisting of washing, extracting, rinsing and extracting, in the order named. Fixed to the top of shaft 88 is gear 89 which through a train of intermediate gears is rotated by the gear 90 fixed to the starter handle shaft 91 operated by the rotatable handle H. Rotation of handle H a suitable distance gives a selective amount of rotation to shaft 88 and all of the cams fixed thereto as will be understood in my said copending application 725,299. The top cam 92 is formed with a depression 93 within which seats the end of arm 94 connected to stem 95 of switch 79. When the free end of arm 94 rests within the depression 93, the switch 79 is opened to disengage contacts 82 and 83 and stop the motor. When cam 92 is rotated with shaft 88 in a counterclockwise direction, as viewed from above, the free end of arm 94 rises up onto the higher peripheral portion of the cam, which moves arm 94 outwardly and closes switch 79 to start the motor.

Cam 96 is provided with two raised portions 97 and 98 and two depressed portions 99 and 100. Opposite cam 96 is a pivoted follower 101 engageable with a valve stem 102 upon which are mounted at fixed spaced distances apart the cleansing and rinsing liquid introducing valve within chamber 50, and the cleansing and rinsing liquid drain valve controlling the chamber 72.

Cam 103 is provided with a single raised portion 104 and an extended depressed portion 105. Opposite cam 103 is a pivoted follower 106 en-

gageable with stem 107 of the valve controlling the chamber within member 56.

Cam 108 is formed with two raised portions 109 and 110 and two depressions 111 and 112. Opposite cam 108 is a pivoted follower 113 engageable with the stem 114 upon which is carried a valve controlling the chamber in member 57.

Cam 115 is provided with two raised portions 116 and 117 and two depressed portions 118 and 119. Opposite cam 115 is a pivoted controller 120 which is engageable with the stem 121 carrying a valve for controlling the compartment in the member 68.

Each of the controller arms 94, 101, 106, 113, and 120 are resiliently urged toward its respective cam so that when the free end of these controller arms drops off from one of the high spots in the cam it will make contact with the depressed peripheral edge portion of the cam.

In Figs. 7 and 8 is shown a vacuum breaker embodying the construction of the vacuum breakers 53 and 59. Each of these vacuum breakers is provided with a casing 122 having in one end an inlet opening 123 and in its side wall an opening 124. These openings are adapted to receive the ends of the pipes leading thereto and therefrom. The upper end of the vacuum breaker is provided with a threaded opening 125 into which is threaded the member 126 provided with a central opening 127. Fixed to the interior of the neck 128 of the casing 122 and extending upwardly into the enlarged chamber 129 is the upper end of the inlet tube, which is provided with a slidably mounted cup-shaped valve 131 having a downwardly extending flange 133. The flange 133 has inwardly directed projections 134, which are spaced around its circumference and slidably contact the outer surface of the tube to maintain the tube and flange in spaced relationship so as to further facilitate the passage of water through the tube into chamber 129 and out through the outlet opening 124. When liquid is being introduced into either the interior of the tub through one of these vacuum breakers or between the diaphragm and the inside of the tub wall through the other vacuum breaker, the pressure of this liquid will force the rubber washer 135 of valve 131 upwardly against the bottom face of plug 126 so as to close the opening 127 and prevent the escape of liquid to the exterior of the casing 122. When, however, the liquid is being drained either out of the interior of the tub or out of the space between the diaphragm and the tub wall the valve member 131 will move downwardly under either gravity or suction or both, and open the hole 127 in plug 126 and thus instantly break any vacuum that might be caused in the pipe system and thus effectively prevent any back flow of liquid into the piping or conduit system.

In the operation of the laundry machine of the present invention the door 26 in the upper portion of the container or tub is opened and clothes or other material to be cleansed are put into the tub or container. At this time the container or tub is stationary. The material to be cleansed may be placed in the tub either before or after introduction of the cleansing liquid as desired. Assuming the material to be cleansed as having been put in the tub first, the handle 47 is then turned to the desired indication of cold, warm or hot, to admit water of the desired temperature from the mixing valve 46 through pipes 48, 49, chamber 50 (its valve then being open), pipes 52, vacuum breaker 53, pipe 54, hose 35, and nozzle

36 into the tub to the desired level therein. The mixing valve 46 is then shut off by handle 47 and any desired amount of detergent is added to the water in the tub.

5 The tub door 26 is then closed and locked, and the lid of the housing is closed. The oscillation of the tub is next started. This is accomplished by turning the starter handle H to the desired position for the particular kind of material being 10 cleansed, which will, through the gears 89—90, rotate shaft 88 and starting cam 92 in a counter-clockwise direction (when viewed from above) sufficient to raise the controller 94 out of depression 93, and as much further as is desired to limit the washing time for the particular material being cleansed. This closes switch 79 and starts the motor, which through suitable mechanism causes oscillation of shaft 30. The tub may oscillate through any desired angle, preferably approximately 90 degrees, at a relatively slow speed, which speed is continuously maintained throughout the washing, extracting and rinsing operations.

20 Before starting the operation of the motor, the 25 parts are in the position shown in Fig. 6, it being kept in mind that all of the cams referred to above are fixed to rotate with the control shaft 88. From Fig. 6 it will be noted that prior to starting the motor the double valve 102 is so 30 positioned as to open the inlet pipe line to the interior of the tub and close the other one of these two valves to prevent drainage of liquid out of the tub. At this time the rinse valve cam 103 is in position to close the rinse valve and the high pressure fluid supply cam 108 is in position to close the valve controlling the high pressure fluid supply. Also the high pressure fluid drain cam 115 is in position to open the high pressure fluid drain valve 121 which will be the position it last occupied at the stopping of the motor following the completion of the previous cycle.

35 As soon as the cleansing operation has been completed this time being controlled by the extent to which the starter handle H has been rotated, 45 the combined wash and rinse water supply cam 96 will have rotated to the position to raise controller arm 101 onto the raised peripheral portion 97 which will close the liquid inlet valve in chamber 50 and open the drain outlet valve in chamber 72. The cleansing liquid is then drained 50 through the nozzle 36, the hose 35, pipe 71, chamber 72, pipes 73, 74, 69, and through the drain pump 78 to the drain. This drain pump is operated continuously during the operation of the 55 laundry machine. Substantially simultaneously with the opening of the drain valve from the tub interior, the high pressure fluid supply cam 108 will, through the raising of the controller 113 by the high peripheral portion 109, as viewed in Fig. 60, open valve 114. This admits high pressure fluid through the operating high pressure pump 64 into the space behind the flexible diaphragm 42 which is the space between the diaphragm and the interior of the tub. This path of water or 65 liquid is from valve 114 through pipe 58, vacuum breaker 59, and pipes 60, 61, 62, and 63, through the operation of the high pressure pump 64. This high pressure fluid is preferably cold water and is admitted through pipe 44 to pipe 55, through valve 114, and thence through the piping 58 to 70 63 as described above. This inflow of high pressure water instantly closes the vacuum breaker 59 and prevents any of this water from escaping to the outside of this pipe line. After leaving high pressure pump 64 this liquid passes upwardly

through the hose 66 and connection 67 into said space behind the diaphragm. It should here be noted that at the time that cam 108 opens the high pressure fluid supply valve the cam 115 has rotated to drop controller arm 120 onto the depressed edge 118, thus closing the high pressure fluid drain valve 121. This causes the diaphragm to be pushed inwardly against the material being cleansed to squeeze the contained liquid therefrom, this operation being simultaneously accompanied by the draining from the tub of the cleansing liquid. As soon as the squeezing of the material being cleansed is completed to the desired degree, the high pressure fluid supply cam 108 reaches a point where the follower 113 drops down onto the depressed peripheral edge 111 which closes the high pressure fluid supply valve 114.

The cam 96 is then rotated to a point to engage the controller arm 101 with the depressed peripheral edge 99 which opens the liquid supply valve 102 and closes the outer one of these two valves in the chamber 72, to admit cold rinse water through the pipes 44, 49, 52, 54, 35 into the tub, it being kept in mind that at this time the high peripheral edge 104 of cam 103 has opened valve 107. It should be remembered that after introducing the warm or hot cleansing water into the tub the mixing valve 46 remains closed hence the rinse water comes from the cold water pipe 44. The arrangement of parts shown in Fig. 6 is such as to enable admitting rinse water to the container or tub, which rinse water fills and overflows the container in a continuous stream and is not shut off until the cams have been rotated a predetermined distance at which time the rinse valve is closed simultaneously with the closing of the container drain valve and the opening of the high pressure fluid supply valve to start collapsing of the diaphragm. It is to be noted that the oscillation of the spherical container or tub is a continuous action, which continues through the entire cycle of the machine. As soon as the rinsing is completed, the controller arm 101, by reason of riding from the depressed edge 99 onto the high edge 98 opens the drain valve in chamber 72 and permits the rinse water to be drained out through pipes 35, 71, 73, 74, and 69 through the drain pump 70. At this time the vacuum breaker 53 is open so that no cleansing or rinse liquid can possibly flow back into pipe line 52.

Simultaneously with the opening of the drain valve in the chamber 72 high pressure fluid supply valve 114 is opened by its cam 108 and the high pressure fluid introduced through the pipe lines 58, 60, high pressure pump 64 and pipe line 63 and 66 into the space behind the diaphragm. This causes the diaphragm to move inwardly as shown in Fig. 5 and squeeze the rinse water from the material being cleansed. When this operation has been completed (which as stated earlier is controlled by the position and extent of the cam offsets) the high pressure fluid drain valve 121 is opened by reason of its cam 115 to drain this high pressure fluid out from behind the diaphragm to the drain pump 70, it being understood that simultaneously the cam 108 by its complementary depressed portion has closed the high pressure fluid supply valve 114.

The clothes or other material being washed are now ready to be removed from the tub, which is effected by opening the lid 17 and the tub door 26. Upon removal of the clothes or other material being washed from the tub, the machine

is then ready to repeat the above described cycle of washing, extracting, rinsing, and extracting referred to. Upon completion of the draining of the high pressure fluid from behind the diaphragm, the cam 92 has reached the point where the controller arm 94 drops into the depression 93 and stops the motor. The next cycle is started when desired by rotating the starting handle and moving the controller arm 94 out of the depression 93 as described earlier herein.

I claim:

1. In a laundry machine, an oscillatable container formed of two hemispherical portions each having an outwardly extending annular flange, said flanges being tightly fixed together to prevent leakage therethrough of liquid from the interior of the container, one of said hemispherical portions having an axial opening in its bottom portion and a pair of oppositely positioned, inner ribs extending from approximately said opening to the respective flange, and the other hemispherical portion having a pair of similar ribs each extending from its respective flange to an upper interior portion of that hemispherical portion, the two ribs of each pair being in alignment and continuous from top to bottom, a flexible diaphragm fixed to the inner surface of the upper hemispherical portion at the top of its ribs, said diaphragm having an opening concentric with said axial opening, a nozzle within the container, a support member on which the container is mounted, said diaphragm and container being tightly clamped between the nozzle base and the support member.

2. A laundry machine comprising, an oscillatable spherical tub having ribs on its interior surface, a flexible diaphragm in said tub, a nozzle in the bottom of the tub, a support member on which the tub is mounted, said nozzle and support member having intercommunicating passageways for forcing cleansing liquid into and draining it from the tub through the nozzle, said support member being fixed to an oscillating shaft for oscillating the tub.

3. A laundry machine as claimed in claim 2, in which the bottom portion of the diaphragm is non-leakably clamped between the nozzle, the tub and the support member.

4. In a laundry machine, an oscillatable container, an upstanding, perforated, conical nozzle in the bottom of the container, a flexible diaphragm fixed to the bottom of the container around the bottom portion of the nozzle, means for forcing the side walls of the diaphragm inwardly toward each other to squeeze cleansing liquid out of material being cleansed in the container, said nozzle having perforations in its upper surface to receive and drain said liquid being squeezed out of said material, a shaft for oscillating the container, a support member fixed to said shaft and upon which the container is mounted, said diaphragm being formed with an opening, said container being formed with an opening, the marginal portions of the container and diaphragm around said openings being clamped between the nozzle and said support.

5. In a laundry machine, an oscillatable container, an upstanding, perforated, conical nozzle in the bottom of the container, a flexible diaphragm fixed to the bottom of the container around the bottom portion of the nozzle, means for forcing the side walls of the diaphragm inwardly toward each other to squeeze cleansing liquid out of material being cleansed in the container, said nozzle having perforations in its

upper surface to receive and drain said liquid being squeezed out of said material, a shaft for oscillating the container, a support member fixed to the shaft for supporting the container, said nozzle having a threaded tubular stem, and said support member having a threaded opening into which said threaded stem is screwed to grip the diaphragm and container between the nozzle and said support member.

6. In a laundry machine, an oscillatable container, an upstanding, perforated, conical nozzle in the bottom of the container, a flexible diaphragm fixed to the bottom of the container around the bottom portion of the nozzle, means for forcing the side walls of the diaphragm inwardly toward each other to squeeze cleansing liquid out of material being cleansed in the container, said nozzle having perforations in its upper surface to receive and drain said liquid being squeezed out of said material, a shaft for oscillating the container, a support member fixed to the shaft for supporting the container, said nozzle having a threaded tubular stem, and said support member having a threaded opening into which said threaded stem is screwed to grip the diaphragm and container between the nozzle and said support member, said support member having a depression, of larger diameter than that of said threaded opening, in which the adjacent portions of the container and diaphragm are seated when gripped between the nozzle and support member.

7. In a laundry machine, an oscillatable container, an upstanding, perforated, conical nozzle in the bottom of the container, a flexible diaphragm fixed to the bottom of the container around the bottom portion of the nozzle, means for forcing the side walls of the diaphragm inwardly toward each other to squeeze cleansing liquid out of material being cleansed in the container, said nozzle having perforations in its upper surface to receive and drain said liquid being squeezed out of said material, the bottom of the container and diaphragm being formed with concentric openings, the marginal portions of the container around its opening being extended downwardly and inwardly to form an annular depressed lip, and the marginal portions of the diaphragm around its opening being bent around and under said lip, a support member having a depression to receive said lip and dia-

phragm bent portion, said nozzle being fastened into said support member to tightly grip said lip and diaphragm portion therebetween.

8. A laundry machine comprising, an oscillatable tub, a perforated nozzle in the bottom of said tub, a motor, a drive shaft driven from the motor for oscillating the tub, a control shaft, a conduit system for introducing cleansing liquid and rinse liquid into the tub through said nozzle and draining it therefrom, cams on said control shaft for controlling steps in a cycle of operations, one of said cams having two circumferentially spaced low portions and two circumferentially spaced high portions, a follower for said one of said cams, a valve member having two chambers and two valves and a common valve stem constantly in engagement with said follower, said conduit system including two branches, one of said branches leading from one of said chambers to said nozzle, and the other of said branches leading from the nozzle to the other one of said chambers, whereby when one of the valves of said valve member is open and the other closed cleansing liquid may be manually introduced into the conduit system and thence into the tub through the nozzle, and when the positions of the valves in the double valve member are reversed cleansing liquid may be drained from the tub through the nozzle.
